United States Patent Office

Des. 184,351
Patented Feb. 3, 1959

184,351

TRANSPARENCY VIEWER

Raymond A. Grosso, Royal Oak, Mich., assignor to Sylvania Electric Products Inc., New York, N. Y., a corporation of Massachusetts

Application June 9, 1958, Serial No. 51,246

Term of patent 14 years

(Cl. D57—7)

Figure 1 is a front perspective view of a transparency viewer, showing my new design;

Figure 2 is a rear perspective view;

Figure 3 is a top plan view;

Figure 4 is a front elevation view; and

Figure 5 is an elevational view of the side opposite that shown in Figure 2.

I claim:

The ornamental design for a transparency viewer, substantially as shown.
